DES
N° 1,157.

J. P. Gallagher
Design for back of stove

Patented Oct. 25, 1859.

Fig A

Fig B

Des 1157

Anthony John Gallagher, of Philadelphia, Pa.

Letters Patent No. 1157. Dated Oct. 26. 1859.

The schedule referred to in these Letters Patent and making part of the same —

To all whom it may concern:

Be it known that I, Anthony John Gallagher, of the City of Philadelphia, in the County of Philadelphia, in the State of Pennsylvania, have invented or produced a new and original design for a Cooking Stove called the "Gas Light Gas Burner" and I do hereby declare that the following is a full and exact description thereof, reference being had to the accompanying drawings and to the letter of reference marked thereon.

Fig. A. No. 1. Represents an oven door of the Stove with its ornaments viz.

A center oval raised figure, with a raised belt and dot radiating from this are raised surfaces representing shells, the first circle of the shells have dots placed upon them.

No. 2 Represents the fire door of Stove with its ornaments viz: same as described in A. No. 1.

Fig. B. No. 3. Represents the back of Stove with its ornaments. viz: A center oval raised figure with a raised belt and dot same as described in Fig. A. No. 1. Radiating from this oval figure are raised surfaces representing shells, and between each row of shells are plain grooved.

All the ornaments or figures are in Alto Reliev.

What I claim and desire to secure by Letters Patent, is the arrangement and combination of the ornaments that form the design herein above specified and represented in the accompanying drawings.

Witnessed

Robt. J. Hayward,
Edgar G. Shultz.

Anthony John Gallagher.
